(57) CLAIM

The ornamental design for a shoe sole, as shown and described.

DESCRIPTION

FIG. 1 is a bottom perspective view of a shoe sole showing my design according to a first embodiment;

FIG. 2 is a side view thereof;

FIG. 3 is a bottom plan view thereof;

FIG. 4 is a rear view thereof;

FIG. 5 is a bottom perspective view of a shoe sole showing my design according to a second embodiment in which at least a portion of the shoe sole is shown as having a transparent or translucent surface;

FIG. 6 is a side view thereof;

FIG. 7 is a bottom plan view thereof; and,

FIG. 8 is a rear view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claimed design.
